UNITED STATES PATENT OFFICE.

THOMAS V. WALLACE, OF MONONGAHELA CITY, PENNSYLVANIA.

DUMP-CAR.

SPECIFICATION forming part of Letters Patent No. 621,186, dated March 14, 1899.

Application filed November 8, 1897. Serial No. 657,822. (No model.)

To all whom it may concern:

Be it known that I, THOMAS V. WALLACE, a citizen of the United States, residing at Monongahela City, in the county of Washington and State of Pennsylvania, have invented certain new and useful Improvements in Dump-Cars; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to certain new and useful improvements in dump-cars.

The invention has for its object the provision of a new and novel means of fastening the end-gate of dump-cars, and is particularly adapted for use in coal-mines.

With the above object in view the invention finally consists in the novel construction, combination, and arrangements of parts, as will be hereinafter more specifically described.

In describing the invention in detail reference is had to the accompanying drawings, forming a part of the specification, and wherein like numerals designate like parts throughout the several views, in which—

Figure 1 is a perspective view showing the end portion of a dump-car fitted with my improved end-gate fastener. Fig. 2 is a face view of the fastener-latch removed from the car. Fig. 3 is a top plan view of the same. Fig. 4 is a perspective view of the stop-block removed from the draw-bar.

Referring to the drawings, the numerals 1 designate the sides of a dump-car, and 2 is the end-gate, which has the cross-bar 3 attached to its upper end and is suspended upon the eyepieces 3' at the upper end of the car-body. To the lower body portion of the car is suitably secured the flat draw-bar 4, and

upon this bar is arranged the block 5, which 45 forms a stop for the latch. Upon the pin 7, which is made fast to the end-gate, is pivoted the latch 6, which has the extended hand-lever *c* formed thereon for operating the latch. The latch when in its normal position, or when 50 closed, enters between stop-block and the outer face of the end-gate, and is prevented from going too far by the pin 12, which is secured to the end-gate. A small space 11 is cut out of the lower end of the gate, so that 55 when the latch is lifted and the car dumped the end-gate may open without interfering with the stop-block 5. A strap 8 is secured to the end-gate by the bolts 9 and 10 and serves to guide the movements of the latch. 60

When the car is to be dumped of its contents, the latch is lifted by means of the lever portion *c*. The car is then tilted and the end-gate swings outward, relieving the car of its contents, and when the car is righted the latch 65 is replaced.

Having thus fully shown and described my invention, what I claim as new, and desire to secure by Letters Patent, is—

In a dump-car, the combination with the 70 end-gate pivoted to the sides of the car at the upper end thereof, and having a central slot or cut-away portion at the lower edge, and the draw-bar provided with a stop-block, of the latch comprising the horizontal portion 75 pivoted at one end to said gate, and the other end bent outwardly and then horizontally forming a handle and the vertical portion adapted to engage with said stop-block, the horizontal guide for said vertical portion and 80 the stop-pin secured to said gate, substantially as shown and described.

In testimony whereof I affix my signature in presence of two witnesses.

THOMAS V. WALLACE.
